J. HATFIELD

SECTIONAL FILING CABINET

Filed Oct. 16, 1924

UNITED STATES PATENT OFFICE.

JOHN HATFIELD, OF BALDWIN, NEW YORK.

SECTIONAL FILING CABINET.

Application filed October 16, 1924. Serial No. 743,887.

My invention relates to filing cabinets or like structures of the sectional type, in which two or any plurality of individual sections or boxes may be placed together to form a multiple stack or unit. The invention especially contemplates the use of sheet metal as the preferred material of the structures, but in its broader aspects it is not necessarily limited in all cases to sheet metal, as other suitable sheet material may be employed. In a more limited respect, however, as expressed in some of the appended claims, sheet metal, usually steel, is employed to provide for high resistance to fire and water, and for other reasons mentioned below.

The general objects of the invention are: To so construct the cabinet sections or boxes, and especially their interlocking members and devices, of suitable sheet material, usually metal, that the production cost is very greatly reduced in comparison with structures heretofore known, while providing at the same time for complete interchangeability of the units, their arrangement in any suitable groups, and the easy and rapid connection or interlocking of the boxes at two or more adjacent corners, and the easy release or unlocking of them for purposes of rearrangement; to provide an attractive front or face finish of the units or boxes, particularly by suitably bending and forming front face flanges of the integral material of the box side, top, and bottom sheets; and to provide an improved and economical rear box wall construction.

The characteristics and advantages of the invention are further sufficiently explained in connection with the following detail description of the accompanying drawing, which show one exemplifying embodiment of the invention. After considering this embodiment, persons skilled in the art will understand that many variations may be made within the principles of the invention, and I contemplate the employment of any structures that are properly within the scope of the appended claims.

Fig. 1 is a front elevation of a stack consisting of several tiers of individual boxes and interlocking devices embodying the invention in one form, illustrative of one of the great variety of possible stack arrangements.

Fig. 2 is an enlarged front elevation show-

ing one complete box or unit and portions of several adjacent units.

Fig. 3 is a section at 3—3, Fig. 2.

Fig. 4 is a section at 4—4, Fig. 2.

Fig. 5 is a perspective view with a part 60 broken away of one form of locking device conveniently called a "rod".

Figs. 6 and 7 are similar views of other forms of locking rods.

Fig. 8 is a plan view of a metal sheet in 65 the flat, cut and ready for pressing to form a box top or bottom wall.

Fig. 9 is a similar view of a sheet ready for pressing to form a side wall.

While the invention is not limited in respect to the size of the individual units, and in fact the units are to be made in a great range of sizes, as sufficiently indicated in Fig. 1, in the form chosen for illustration the invention is especially designed for units 70 of moderate size, such as those intended to contain cards or similar records of moderate area; but evidently with or without modification, the invention is adapted to boxes of 75 any reasonable size, for example, those intended to hold drawers containing letter or legal size folders or the like. While the individual units or boxes are well adapted as here shown to receive drawers, the employment of drawers is not necessary and 80 the units or stacks may be used to contain almost any kind of articles or commodities 85 whether placed in drawers or not.

The top and bottom walls of each unit or box are composed of sheets S, Fig. 8, which 90 may be identical. The side walls are composed of sheets S¹, Fig. 9, which may be identical. The rear wall consists of a sheet R. For the complete box therefore, only five sheet metal parts are required, two of 95 which, namely, the top and bottom sheets, may be of identical shape and two others, namely, the side sheets, may also be identical, requiring the production of only three sets of sheets S, S¹ and R for boxes of any 100 given dimensions.

Sheets S are of generally rectangular outline but are cornered, that is to say, corner pieces are cut out to form side margins 1, a front margin 2 and a rear margin 3, these marginal portions or strips being subsequently folded by pressing operations, as indicated by dot-and-dash lines. Sheets S¹ are also cornered to provide top and bottom marginal strips 4, a front marginal strip 105 110

5 and a rear marginal strip 6, these also being subsequently folded by pressing operations, as sufficiently indicated by dot-and-dash lines. The sheets and the complete structure are so devised that after cutting, the sheets may be folded to final form by very simple operations, usually by a single pressing action with a single set of relatively simple and inexpensive dies. The cost of production is thus materially reduced, both by reason of the simplicity and moderate amount of materials employed, and the simplicity of the manufacturing operations, which entails a very moderate outlay for tool equipment.

Sheets S when pressed, have shallow locking flanges 10 extending at right angles to the sheet body, these flanges consisting of the margins 1 of the original sheet. The sheets also have front or face formations comprising vertical flanges or front webs 11 and inturned webs or flanges 12 which are respectively at right angles and parallel to the main sheet body. At their rear edges the sheets have inturned flanges or hooks 13 formed from the margins 3.

Each side sheet has a front formation comprising an angular web 14, a front web 15 extending at a right angle to the sheet, and an inturned web 16 parallel to the sheet body and spaced slightly from it. Each of these sheets also has at its rear edge, an inturned or hooked flange 17. These webs are produced from the sheet margins 5 in the pressing operations. The webs 14 and 15 are connected by vertical corner formations 18. The side margins 4 are also bent at right angles to the sheet body forming flanges 20.

Two of the pressed sheets S, and two of the sheets S¹ are then put together in the positions sufficiently indicated in Figs. 2, 3 and 4, and secured in box form in any suitable way, usually for the sake of economy and strength by spot welding. The main bodies or walls of sheets S¹ then constitute the side walls of the box which is open at the front and back, and the sheets S constitute the top and bottom walls.

The sheets R constituting the back walls are pressed or otherwise formed in any suitable way with right-angle marginal flanges 22 on all four sides. These flanges may be continuous or separated at their meeting ends. Preferably, to provide for better interlocking of the rear walls with the side, top and bottom walls, the opposite flanges 22 of the back piece R are formed with rounded beads 23, so arranged that when viewed from any position, such as from the bottom of Fig. 4, the concave faces of the beads front the same way. These beads or ribs may be pressed either in the top and bottom or the two sides, or, as shown, in all four of the flanges of the back piece.

To correspond with these bead or rib formations mating ribs or beads 24 are formed in the top, bottom and side sheets S and S¹, the concave sides of the opposite beads also fronting in the same direction. Flanges 1 70 and 4 of sheets S and S¹ are so dimensioned in the original cornering operation that their rear ends 26 terminate considerably forward of the hooked members 13, to provide room for the back plate flanges. 75

After the top, bottom and side walls have been connected by spot welding flanges 4 to the top and bottom sheets in such positions that the main sheets are located slightly inward from locking flanges 10, as best 80 shown in Fig. 4, the rear ends or back plates are put in position by tilting them and inserting them from the open front of the box. By tilting, the beads 23 and 24 of the back piece, the top and bottom plates 85 respectively are brought into registry, and the peripheral edges of the flanges 22 are then pushed under the locking flanges 13 and 17, and if necessary these flanges or hooked margins may be rolled down to more 90 firmly secure the back plates.

In the cornering operations on sheets S and S¹ marginal strips 2 and 5 are so dimensioned that when bent up as described, the ends of these margins will properly abut. 95 For example, as best shown in Fig. 2 the ends of the web or flange portions 15 and 16 are dimensioned so they fit closely against end portions of the faces of the inturned flanges 12; while the ends of the web or flange portions 11 and 12 are positioned to come in the same planes as the outer faces of the vertical side sheets S¹. There is thus left at each longitudinal corner of each box, a space 30 giving access to the locking 105 flanges 10, this space being large enough to accommodate the locking rod.

Figs. 5, 6 and 7 sufficiently show three different forms of locking rods L, L¹ and L². Other forms may be provided when necessary or desirable. The form L, as shown in Fig. 5, is for securing two superposed boxes together along their meeting corners, as at the point P, Figs. 1 and 2. This rod may consist of a single strip of sheet metal, both longitudinal margins of which are bent over to form hooks 31, these hooks preferably consisting of distinct webs 32 and 33, joining each other and the main outer web 34 with sharp angles or corners to correspond with the preferred sharp bends which connect the locking flanges 10 with sheets S. This is to provide co-operation of the flanges and hooks and permit free sliding of the locking rods into position 110 without jamming, but without appreciable play. At one end the space defined by the locking hooks is preferably closed by a narrow end margin of the main web 34 bent at a right angle to form a flange 35. This 115

provides a smooth and slightly outer end finish for the rod. When any two of the sections or boxes such as B, Figs. 1 and 2, have been placed in superposed relation, they are secured together at adjacent corners by so placing the open or inner ends of locking rods L as to properly co-operate with the outer ends of the locking flanges 10, and then pushing the rod in until its end 10 flange 35 encounters the ends of the locking flanges. Flange 35 is then flush with the facing webs 11 and 15, only a very small or no appreciable space being left at the upper and lower ends of the flange 35.

15 To provide for interlocking where four longitudinal box corners come together as at P¹, Figs. 1 and 2, a locking rod L² is provided, as shown in Fig. 7, which consists substantially of two of the rods L placed together back to back and secured by spot welding or in any other suitable way. The locking hooks of this rod will co-operate with the four adjacent locking flanges 10 in a way which will be obvious from inspection 20 of Fig. 2. To provide for cases where two boxes or sections are located side by side, as at P², Figs. 1 and 2, a rod L¹, Fig. 6, is provided. This is in general similar to the rod L², two of the locking hooks, however, being omitted and replaced by simple right angled 25 flanges 40. When inserted to connect two adjacent boxes as at P², in an obvious way, the aligned flanges 40 form a presentable outer finish or surface at the line of box intersection which is practically flush with the top or bottom box surfaces. When any 30 two boxes are brought together side by side a close fit is provided by the vertical corner formations 18 which closely abut, without any appreciable crack or space. When any 35 two boxes are brought together vertically the flush bottom and top surfaces respectively meet closely, without appreciable gap.

40 Fig. 1 shows a representative stack arrangement of boxes of at least three different sizes or dimensions B, B¹ and B². Where the vertical dimensions vary, as with respect to boxes B and B¹, or B and B², the different dimensions are so related that the horizontal intersections of superposed boxes in 45 different tiers will come together at intervals. For instance, three superposed boxes B¹ match with two superposed boxes B, and five of the superposed boxes B² match with four of the boxes B. In this way interlocking connection is provided at intermediate points 50 between the different tiers of boxes or else at least at the top and bottom of the stack when a reasonable number of boxes are placed in each tier, and interlocking connection is, of course, provided at each side of every superposed box in any tier. Any box or boxes may be easily unlocked for rearrangement by pushing the locking rods out 55 slightly from the back and then pulling them

all the way out from the front of the stack.

Evidently the front margins or face formations of the units may be varied considerably by different bending of the marginal strips 2 and 5, but the form shown is preferred in some cases. Particularly, the inward flanges 12 and 16 provide smooth guides at the front of the box for a drawer, when a drawer is inserted. The bottom or the bottom edges of the side rails of the drawer will 70 slide on the lower flange 12, while the sides of the drawer are guided by the vertical flanges 16. At the back the drawer may have a depending portion which will slide on the main surface of the bottom sheet S, this depending drawer portion having a depth equal to the vertical distance between flange 12 and the main sheet so as to maintain the drawer in horizontal position as it slides on the two points of support. The depending 75 rear portion of the drawer will also act as a stop co-operating with the edge of the lower flange 12 to prevent inadvertent withdrawal of the drawers. The drawer structure is not illustrated, because such structures may vary 80 greatly and the drawer proper does not form a part of the present invention.

85 While a great many different types or forms of sectional cabinets have been proposed or used, and some of these forms or systems consist of sheet metal structures, they have been unduly complicated and expensive, or have involved the use of a number of bolts or other devices which involve considerable time and labor, or are unduly complicated, for connecting them together. Sections or boxes and the interlocking devices made in accordance with my invention however, require probably the least possible 90 number of separate parts, which may be 95 economically put together with moderate shop equipment, and the locking devices are exceedingly simple and easily manipulated so that a large number of sections can be 100 quickly put together or rearranged, without 105 any risk of losing small parts, such as bolts or other small fastening devices.

I claim:

1. A box-like unit adapted for sectional cabinet arrangements and comprising longitudinal walls in substantially rectangular arrangement, two opposite walls having at their longitudinal edges substantially hook shaped locking flanges spaced slightly away from the other adjacent walls, the flanges at each side of the box structure being turned toward each other and being adapted, when two of the boxes are placed together, to receiving locking rods of generally channel, hooked formation which hold the backs 115 of the locking flanges and the walls which carry them in immediate contact.

120 2. A unit for sectional cabinet arrangements composed of metal sheets and comprising opposite longitudinal walls having 125

substantially smooth and flush outer surfaces admitting the placing of a similar wall of another unit in close flush contact therewith, and also having inwardly directed 60
5 substantially hook shaped locking flanges at their longitudinal edges, and two other opposite walls having inturned flanges secured to the walls first mentioned, with said other opposite walls located slightly inward from the locking flanges to provide clearance for locking rod members.

3. A unit for sectional cabinet arrangements composed of metal sheets and comprising opposite longitudinal walls having inwardly directed locking flanges at their longitudinal edges, and two other opposite walls having inturned flanges secured to the walls first mentioned, with said other opposite walls located slightly inward from the locking flanges to provide clearance for locking rod members, two opposite walls having their front margins bent to form webs projecting diagonally forward and outward, facing webs lying in the plane of the 70
15 unit front, and flanges turned inward parallel to the main walls, the diagonal and front or facing webs being joined by edges located approximately in the plane of the locking flanges to form a close meeting line between 75
20 adjacent boxes or sections.

4. A sheet metal section or unit for sectional cabinet arrangements, comprising sheet metal top, bottom and side walls and a back wall having its margins bent to form 80
35 right-angle flanges lying against the top, bottom and side walls, said walls having in-turned marginal hook formations overlying the edges of the rear wall margins, two opposite rear wall margins and adjacent portions of the corresponding longitudinal 85
40 walls being beaded in a corresponding direction to provide for interfitting of the bead formations on adjacent sections.

5. A sectional filing cabinet system comprising a plurality of individual boxes or units, each of which comprises opposite longitudinal walls having substantially smooth and flush outer surfaces admitting the placing of a similar wall of another unit in close flush contact therewith, and also having inwardly directed locking hooks at their longitudinal edges, and two other opposite walls having inturned flanges secured to the walls first mentioned, with said other opposite walls located slightly inward from 90
50

the locking hooks to provide clearance for locking rod members, and locking rods of sheet metal having their longitudinal margins bent to form longitudinal hooks to co-operate with the locking hooks of adjacent 100
60 sections.

6. A sectional filing cabinet system comprising a plurality of individual boxes or units, each of which comprises opposite longitudinal walls having locking flanges at their longitudinal edges, the locking flanges at each side of the box structure being turned toward each other, and two other opposite walls having inturned flanges secured to the walls first mentioned, with said other 70
15 opposite walls located slightly inward from the locking flanges to provide clearance for locking rod members, certain of the walls having their front margins bent to provide facing strips and inturned guide flanges at 75
20 the front of the box or unit, and locking rods of sheet metal having their longitudinal margins bent to form longitudinal hooks to co-operate with the locking flanges of adjacent sections.

7. A sectional filing cabinet system comprising a plurality of individual boxes or units, each of which comprises opposite longitudinal walls having locking flanges at their longitudinal edges, the locking flanges 80
85 at opposite sides of the box structure being turned toward each other, and two other opposite walls having inturned flanges secured to the walls first mentioned, with said other opposite walls located slightly inward 90
95 from the locking flanges to provide clearance for locking rod members, two opposite walls having their front margins bent to form webs projecting diagonally forward and outward, other facing webs lying in the plane of the box or section front, and flanges turned inward parallel to the main walls, the diagonal and front or facing webs being joined by edges located approximately 100
100 in the plane of the locking flanges to form a close meeting line between adjacent units, and locking rods of sheet metal having their longitudinal margins bent to form longitudinal hooks to cooperate with the locking flanges of adjacent sections.

Signed at New York in the county of New York and State of New York this 14th day of October A. D. 1924.

JOHN HATFIELD.
